ASTERN ATTACK TOW TARGET

John W. Griesinger, Dayton, Ohio

Application May 27, 1944, Serial No. 537,672

5 Claims. (Cl. 273—105.3)

(Granted under the act of March 3, 1883, as amended April 30, 1928; 370 O. G. 757)

1

The invention described herein may be manufactured and used by or for the Government for governmental purposes, without the payment to me of any royalty thereon.

This invention relates to aerial gunnery targets and particularly to that class of targets which are intended to be attacked while being towed from the stern of an aircraft.

It is a part of Army gunnery training to attack an aircraft from astern, the trainee, for practice, being required to fire at a towed target from the rear. To fire into the rear of an ordinary tow target, however, is extremely hazardous for the aircraft which is doing the towing, yet heretofore no satisfactory device has been provided which obviates this danger.

It is therefore an object of the invention to provide a tow target which is particularly adapted to lessen this hazard of the towing plane. More particularly it is an object to so construct the target that it will take a path which is parallel to the path of the towing plane but considerably below it or considerably to the right or to the left of it as may be desired.

Other objects and advantages will be evident as the invention is further described with reference to the drawings wherein—

Fig. 1 is a side elevation of my improved tow target.

Fig. 2 is a front end view of the device.

Figs. 3 and 4 disclose two of the several ways in which the device may be loaded to alter its path with respect to the path of the towing plane.

Fig. 5 shows one of the sand bags, a plurality of which are employed to determine the path of the device with respect to the towing plane.

In the drawings, a hollow cone 10 comprises a plurality of sectoral panels 12 joined together by seams 14, all seams being reinforced by webbing 16. A single panel 18 has its sides joined to the other panels to complete the cone, the panel 18 being cut away as at 20 for a purpose which will later appear.

Panels 12 are composed in greater part of a relatively close woven cloth which is substantially impervious to the passage of air, while the entire panel 18 and a small part 19 of each sectoral panel 12 near the apex is made of a relatively coarse woven mesh through which air may pass quite freely. The perimeter of the base of the cone 10 is reinforced by a heavy cord 22.

Attached to the perimeter of the base of the cone 10, preferably at the reinforcing of the joints between panels, are a series of bridle lines

2

24, the free ends of which are brought together as at 26 to form a loop to which the line from the towing plane may be connected.

Stitched to the surface of the cone 10 at the base are several layers of fabric 28, the stitching being so spaced as to form pockets for the sand bags 30, Fig. 5. It is the circumferential position of the sand bags 30 with respect to the cut away portion 20 which determines the offset 10 between the course of the target and that of the towing plane.

Fig. 3 is a diagrammatic view of the cone 10 viewed from the rear or apex end. Here the perforate cut away panel 18 is angularly spaced 15 180 degrees from the sand bag load, which, of course, is drawn to the bottom by gravity. When the target, arranged as in Fig. 3, is being towed, air is forced laterally through the perforate panel 18 and simultaneously spills from the cut away portion 20, so that the reaction of the air moving laterally in one direction tends to move the target laterally in the opposite direction, whereby the target will take a course parallel to, but considerably below that of the towing plane. 25 On the other hand, if the perforate panel 18 is angularly spaced less than 180 degrees from the bottom to which the sand load gravitates, as for instance, to the left of top center, as seen in Fig. 4, the target will ride a course which is below 20 but also to the right of the course taken by the towing plane.

Other positioning of the perforate panel 18 with respect to the load position will result in still other relative offsets between the towing plane's 35 course and the course of the target.

While the weight means 28-30 is carried on the convex surface of the cone near the base, it will, of course be understood that it may be supported in any convenient position which is eccentric to 40 the cone axis, and while the opening 20 is made in the panel 18 adjacent the base, it may be made in any part of the perforated panel 18, or the panel 18 may be made of imperforate fabric and the opening 20 made sufficiently larger to compensate for the lack of small perforations, the object being to provide a lateral discharge of air from the cone which will react and deflect the cone oppositely from its normal path beyond the towing plane. Moreover, while the body of 45 the target is in the form of a cone, any other suitable shell having the forward end open and the rearward end closed or partly closed will be considered within the scope of the invention.

Having described an embodiment of my invention, I claim:

1. A tow target, adapted for astern attack, which comprises a hollow shell open at the forward end and having at least one lateral opening in its side wall, means for attaching a towline to the open end of the shell, and a weight means carried on the shell eccentrically disposed with respect to the shell axis and angularly spaced from said lateral opening.

2. A tow target, adapted for astern attack, which comprises a hollow shell open at the front end and having at least one lateral opening in the side wall, means for attaching a towline to the front end of the shell, and a weight means carried on the side wall of the shell near the base angularly spaced from the lateral opening.

3. A tow target, adapted for astern attack, which comprises a hollow conical shell having its side wall made up of a plurality of triangular panels, at least one of said panels being composed of highly perforate material and the remainder of the panels having a lesser portion perforate, means for attaching a towline to the base of the conical shell, and a weight means carried on the shell eccentrically disposed with respect to the shell axis and angularly spaced from said perforate panel.

4. A tow target adapted for astern attack, which comprises a hollow cone with an open base

and the side wall made up of a plurality of triangular panels, at least one triangular panel being composed of highly perforate material, the remainder of the triangular panels being composed of imperforate material except for a small area at the apex of each triangle which is composed of perforate material, means for attaching a tow line to the open base of the cone, and a weight carried on the side wall of the cone near the base angularly spaced from the perforate panel.

5. A tow target adapted for astern attack, which comprises a hollow cone with an open base and the side wall made up of a plurality of triangular panels, at least one triangular panel being composed of highly perforate material and having a portion cut away at the base to provide a relatively large lateral opening in the cone side wall, the remainder of the triangular panels being composed of imperforate material except for a small area at the apex of each triangle which is composed of perforate material, means for attaching a tow line to the base of the cone, and a weight carried on the side wall of the cone near the base angularly spaced from the perforate panel.

JOHN W. GRIESINGER.
